[57] **CLAIM**

The ornamental design for a combined electrode drive and nozzle unit for an automatic air carbon-arc cutting and gouging torch, as shown and described.

DESCRIPTION

FIG. 1 is a front elevational view of a combined electrode drive and nozzle unit for an automatic air carbon-arc cutting and gouging torch showing our new design;
FIG. 2 is a top plan view thereof;
FIG. 3 is a rear elevational view thereof;
FIG. 4 is a bottom plan view thereof;
FIG. 5 is a right side elevational view thereof;
FIG. 6 is a left side elevational view thereof.

FIG. 2

FIG. 1

FIG. 3

FIG. 4

FIG. 5

FIG. 6
